(57) **CLAIM**

The ornamental design for a foam lid insert, as shown and described.

DESCRIPTION

FIG. 1 is a top, front, right side perspective view of a foam lid insert, showing the new design;

FIG. 2 is a front elevation view;

FIG. 3 is a rear elevation view;

FIG. 4 is a left side elevation view;

FIG. 5 is a right side elevation view;

FIG. 6 is a top plan view;

FIG. 7 is a bottom plan view; and,

FIG. 8 is a top, front, right side exploded perspective view. The broken lines shown are for the purpose of illustrating environmental structure and form no part of the claimed design.
